(57) **CLAIM**

The ornamental design for a banana crate, as shown and described.

DESCRIPTION

FIG. 1 is a top perspective view of a banana crate according to my new design in an unfolded state;

FIG. 2 is a bottom perspective view thereof in an unfolded state;

FIG. 3 is a top perspective view thereof in a folded state;

FIG. 4 is another top perspective view thereof in an unfolded state;

FIG. 5 is another bottom perspective view thereof in an unfolded state; and,

FIG. 6 is another top perspective view thereof in a folded state.

In the drawings, the broken lines depict unclaimed subject matter only and form no part of the claimed design.

1 Claim, 6 Drawing Sheets

FIG. 1

FIG. 3

FIG. 5
